UNITED STATES PATENT OFFICE.

GEORGE E. PANCOAST, OF BROOKLYN, NEW YORK, ASSIGNOR TO AMERICAN LITHOGRAPHIC COMPANY, A CORPORATION OF NEW YORK.

PRINTING MECHANISM.

1,106,472.

Specification of Letters Patent. Patented Aug. 11, 1914.

Application filed November 8, 1902, Serial No. 130,499. Renewed December 3, 1904. Serial No. 235,334.

To all whom it may concern:

Be it known that I, GEORGE E. PANCOAST, a citizen of the United States, resident of the borough of Brooklyn, county of Kings, 5 State of New York, have invented new and useful Improvements in Printing Mechanism, of which the following is a specification.

My invention relates to printing mechanism and especially to mechanism for back printing or perfecting paper which has been printed in colors on one side.

In applying the rotary press principle to the better grades of printing great difficulty 15 has been experienced in preventing the "offset" which takes place in the second or perfecting printing mechanism. The offset is due to the fact that part of the ink applied to the paper by the first printing couple 20 is deposited on the impression surface of the second printing couple, which surface after a few impressions becomes so charged with ink as to cause a smut or "offset" on the surface of the paper which comes in 25 contact therewith. Many devices have been used to prevent this charging of the impression surface of the second printing couple with the ink of a previous impression. A common way of effecting this purpose consists in leading a web of paper between the 30 second impression surface and the paper being printed. This method is objectionable, however, because the offset web removes a part of the ink of the first impression on the 35 paper being printed and thus very materially reduces the gloss or brilliancy of that impression. This defect is very marked in multicolor work and especially in multicolor lithographic work. This method is expensive, moreover, because the web has to be 40 frequently renewed, and a more or less complicated mechanism is required to handle the web. When applied to web presses, this mechanism requires considerable space in 45 the machine and on this account also it is objectionable and not capable of universal application.

My invention has for an object to provide a perfecting printing mechanism, the impression surface of which is of such a nature 50 that it will not receive a deposit of ink from the previous impression or impressions on the paper; also to provide a mechanism of the character referred to, which is simple 55 in construction and operation, and in which

the ink-repelling characteristic of the impression surface may be perfectly developed and permanently maintained. These and other objects of my invention will more fully appear from the following description. 60

My invention consists in the novel parts, improvements and combinations herein shown and described.

The accompanying drawing, which is referred to herein and forms a part hereof, 65 illustrates one embodiment of my invention and serves in connection with the description herein to explain the principles thereof and the best mode contemplated by me of carrying these principles into effect. 70

The drawing consists of a diagrammatic view illustrating a multicolor printing press with a perfecting printing couple constructed in accordance with my present invention associated therewith, the cylinders of the 75 perfecting couple being shown in section.

Referring to the drawing in detail, 1 represents the frame of the machine, 2 a large central impression drum, and 3 a series of design cylinders arranged circumferentially 80 around the drum and adapted to be brought into printing contact therewith. Each design cylinder is provided with an inking mechanism 4 and preferably also with a damping mechanism 5. A web of paper 6 is 85 led from a supply roll 7 around the impression drum 2, where it receives on one of its surfaces a series of impressions from the design cylinders 3.

In accordance with the construction 90 shown in the figure, the web after having passed under all of the design cylinders 3 is led away from the impression drum 2 over a suitable guide roller 8 and is passed through the perfecting printing mechanism 95 shown at the bottom of the figure.

In accordance with my invention this perfecting printing mechanism comprises a printing member having a yielding design surface and an impression member having a 100 rigid ink-repelling impression surface. Preferably the ink-repelling characteristic of the impression surface is produced by moisture, means being provided in the machine to keep the impression surface in a 105 moist condition. According to the preferred construction, also, the yielding design surface is in the form of a transfer or secondary design surface which receives its design from a suitable rigid primary design surface. 110

The perfecting printing mechanism shown consists of a primary design cylinder 9, a secondary printing cylinder 10, and an impression cylinder 11. Primary cylinder 9 is provided with a suitable inking mechanism 12 and, where it is planographic in character, with a suitable damping mechanism 13 also.

The impression cylinder 11 is preferably 10 provided with a surface which may be developed and made ink-repelling upon the principle of the non-printing portions of a lithographic design surface, that is to say, it is made of such a material or is given such 15 a surface character or texture or porosity that when the gummed and etched in substantially the same way that lithographic design surfaces are gummed and etched it will, at every part of its surface, when 20 moistened, refuse to take or hold any ink or other greasy substance. It is to be noted in this connection that no surface, which maintains a film of moisture merely mechanically, even though the surface is porous and 25 is treated with an acid to remove all traces of grease and thoroughly clean it, will be permanently ink-repelling. It is essential that the surface be so constituted and treated that it will not absorb ink even if 30 ink is applied when the surface is dry. Something more than a mere mechanical separation of the ink from the impression surface by a film of water is required. The surface must be incapable when moistened 35 of retaining any grease that may have been applied to the surface when it was dry.

In accordance with my invention the surface is preferably made of zinc or aluminum, but other porous metallic surfaces may 40 be used, or the surface may consist of lithographic stone, or other suitable calcareous substance. The required permanent ink-repelling quality of the surface is obtained by treating the same with a solution of gum 45 arabic to which a small quantity of a suitable acid has been added. The acid should be such as will not materially corrode the surface, the purpose of the acid being not so much to bite or etch the surface as to set 50 or harden the gum. Where zinc or a similar metallographic metal is used, phosphoric acid is suitable. Nitric acid is preferable where a calcareous substance is used. Such an ink-repelling surface, however, is sensitive and short-lived as compared with the 55 ordinary impression surface, and if it were made flexible or yielding, as impression surfaces have been heretofore universally made in practice, it would soon be destroyed or 60 rendered ineffective by the continual bending or flexing caused by the rolling contact with the design surface under the heavy pressure required in printing. To avoid these difficulties, the impression surface in 65 accordance with my invention is, when in

place, substantially rigid and inflexible and the design surface is made somewhat yielding or flexible, so that it will coöperate with the impression surface and produce perfect impressions without subjecting the impression surface to a destructive pressure or wear. When the impression surface is to be used in a rotary press it is formed or mounted on a cylinder, and in order that it may be readily removed from the press and another substituted in its place at intervals, as is required on account of its short life, the impression member is preferably made thin and light and is removably secured to a rigid supporting cylinder 14. 70 75 80

A suitable damping mechanism is provided for continuously applying moisture to the surface of the impression member 11. As indicated in the drawing this damping mechanism may consist of a pair of applying rollers 15, a distributing roller 16, a ductor 17, and a fountain roller 34 mounted in the fountain 18. 85

The design member 10 which coöperates with the impression member 11 may be provided with any form of design surface which is substantially flexible or yielding in its nature. Preferably the surface of the design member 10 is formed of a suitable rubber composition which may consist of an 90 inner layer 19 of hard rubber and an outer thin layer 20 of softer rubber, the whole being vulcanized in place upon the outer 95 surface of the inner supporting cylinder 21, and then turned and ground or otherwise 10 given a suitable shape and surface finished.

The primary design cylinder 9 may be of any suitable construction and may be provided with any desired form of design surface, relief or lithographic. 10

Any suitable means (not shown) may be provided for separating the cylinders 9, 10 and 11 and for bringing them together again with the necessary pressure, and for moving the inking and damping mechanism into and 11 out of contact with the cylinders 9 and 11, as is required in stopping and starting the printing operation of the press.

It is among the advantages of my invention that the cumbersome and troublesome offset web may be dispensed with in the perfecting printing mechanism; that none of the ink of the first impression or impressions is removed by the perfecting operation; that the perfecting mechanism with its accessories occupies but little more space in the press than an ordinary non-perfecting printing couple and therefore may be so located in the machine that the web passes directly to it from the multi-color printing mechanism, 11 and that the construction is simple and durable and reliable in operation and may be cheaply maintained. When the preferred forms of design and impression members are used, little or no preparation or "make 1

ready" is required to put the press in condition for the printing operation.

5 My invention in its broader aspects is not limited to the precise construction shown and described, nor to the precise construction by which it may be carried into effect, as many changes may be made therein without departing from the main principles of the invention and without sacrificing its main 10 advantages.

What I claim as new, and desire to secure by Letters Patent, is:—

1. In a printing press, the combination with a design member having a yielding 15 surface, of an impression member having a rigid ink-repelling impression surface, substantially as described.

2. In a printing press, the combination with a design member having a yielding 20 surface, of an impression member comprising a support and a removable and replaceable impression device having a rigid ink-repelling impression surface, substantially as described.

25 3. In a printing press, the combination with a design member having a yielding surface, of an impression member having a rigid impression surface which when moistened becomes ink-repelling, and means for moistening the impression surface, substantially as described.

30 4. In a printing press, the combination with a design member having a yielding surface, and an impression member comprising a support and a removable and replaceable impression device having a rigid impression surface which when moistened becomes ink-repelling, and means for moistening the impression surface, substantially as 40 described.

45 5. In a rotary printing press, the combination with a design cylinder having a yielding surface, of an impression cylinder having an ink-repelling impression surface, substantially as described.

50 6. In a rotary printing press, the combination with a design cylinder having a yielding surface, of an impression cylinder comprising a rotary support and a removable and replaceable impression device having an ink-repelling surface, substantially as described.

55 7. In a rotary printing press, the combination with a design cylinder having a yielding surface, of an impression cylinder comprising a rotary support and a removable and replaceable impression device having an impression surface which when moistened becomes ink-repelling, and means for moistening the impression surface, substantially as described.

60 8. In a rotary printing press, the combination with a primary design member, of a secondary design member having a yielding surface, an impression member having a

rigid ink-repelling impression surface, substantially as described.

9. In a rotary printing press, the combination with a primary design cylinder, of a secondary design cylinder having a yielding 70 surface, of an impression cylinder comprising a rotary support and a removable and replaceable impression device having an impression surface which when moistened becomes ink-repelling, and means for moistening the impression surface, substantially as described.

10. In a multi-color printing press, the combination with a plurality of design members for printing on one side of the paper, 80 of a perfecting design member having a yielding surface, and an impression member for the perfecting printing member, the impression member having a rigid ink-repelling impression surface, substantially as described.

11. In a rotary multi-color printing press, the combination with a plurality of design cylinders for printing on one side of a web, 90 of a perfecting design cylinder having a yielding surface, and an impression cylinder for the perfecting printing cylinder, said impression cylinder having an ink-repelling impression surface, substantially as described.

95 12. In a multi-color printing press, the combination with a plurality of design members for printing on one side of the paper, of a perfecting design member having a yielding surface, an impression member for the perfecting printing member, the impression member having a rigid impression surface which when moistened becomes ink-repelling, and means for moistening the impression surface, substantially as described.

100 13. In a rotary multi-color printing press, the combination with a plurality of design cylinders for printing on one side of a web, of a perfecting design cylinder having a yielding surface, an impression cylinder for 110 the perfecting printing cylinder, said impression cylinder having an impression surface which when moistened becomes ink-repelling, and rollers for applying moisture directly to the impression surface, substantially as described.

115 14. A multicolor web printing press including in combination, a circumferentially continuous impression drum, a plurality of circumferentially continuous planographic 120 design cylinders arranged to coöperate with said impression drum to print one side of the paper, and means for printing a design on the other side of the paper, while the ink applied to the first side thereof is in a 125 fresh or undried state and without removing any of the ink applied to the first side, the web being led directly from the first printing mechanism to the second printing mechanism, substantially as described.

4

15. A rotary multicolor printing press including in combination, an impression drum, a plurality of design cylinders for printing on one side of the paper carried by the drum, and means comprising an impression member having a circumferentially continuous rigid ink-repelling surface, and a suitable design member for printing on the other side of the paper, while the ink applied to the first side thereof is in a fresh and undried state.

16. A printing press including in combination, a design member having a yielding surface and an impression member having an ink repelling surface.

17. A rotary multicolor printing press including in combination, a plurality of design cylinders for printing on one side of the paper, and means including a design cylinder having a yielding surface and an impression member having an ink repelling surface for printing on the opposite side of the paper.

In testimony whereof, I have signed my name to this specification, in the presence of 25 two subscribing witnesses.

GEORGE E. PANCOAST.
